UNITED STATES PATENT OFFICE.

RUFUS E. MOODY, OF NOVA, OHIO.

MAIL-BAG CRANE.

1,145,257.

Specification of Letters Patent.

Patented July 6, 1915.

Application filed March 11, 1915. Serial No. 13,643.

To all whom it may concern:

Be it known that I, RUFUS E. MOODY, a citizen of the United States, residing at Nova, in the county of Ashland and State of Ohio, have invented certain new and useful Improvements in Mail-Bag Cranes; and I do declare the following to be a full, clear, and exact description of the invention, such as will enable others skilled in the art 10 to which it appertains to make and use the same.

This invention relates to improvements in mail bag cranes for supporting mail bags in position to be caught by the catcher hook 15 on the mail car of a moving train.

The object of the invention is to provide a simply constructed crane which is adapted to operate in such a manner as to sustain the bag to permit it to be caught by the 20 catcher hook of a train moving in either direction along the track or it may be used on a mail car for delivering a mail bag to a catcher hook disposed along the track.

Another object of the invention is to provide 25 a mail crane having a swinging bag supporting member adapted to swing in either direction and to normally remain out of operative position so that it will not constitute a source of danger to passengers on moving trains or to others, such as brakemen on freight trains.

With these and other objects in view, the 30 invention consists of certain novel features of construction, and the combination and arrangement of parts as will be more fully described and claimed.

In the accompanying drawings: Figure 1 35 represents a side elevation of a mail crane constructed in accordance with this invention and showing a mail bag supported thereby, in dotted lines; Fig. 2 is a front elevation thereof showing the device in operative position in full lines and in inoperative position in dotted lines; Fig. 3 is a detail perspective view of the frame supporting means.

In the embodiment illustrated a support 1 is here shown which may be mounted at one side of a railroad track or in the doorway 40 of a mail car. Mounted to swing on this support 1 is a bag supporting frame 2 herein shown in the form of a rod having right angularly disposed arms 3 and 4 extending from its opposite ends to provide engaging means for the mail bag B which is provided 45 at its opposite ends with the usual loops L.

The body portion of this frame 2 is disposed in upright position on the support 1 and is held at its lower end by a clip 5 herein shown formed of strap iron secured at its 50 opposite ends to the support 1 and having an outbowed portion 6 intermediate of its ends to form a bearing for the body portion of the frame 2 as is shown clearly in Figs. 1 and 2. The upper end of the frame 2 is 55 supported by a bracket 7 which is herein shown constructed of a curved plate secured at its opposite ends to the side edges of the support 1 by means of bolts 8 or other suitable fastening elements. This bracket or 60 plate 7 is substantially U-shaped in cross section to provide ample space between it and the support 1 to permit the free movement of the frame 2 between it and said support. The upper edge of this plate 7 is 65 provided midway its width with a curved recess 9 in which the arm 3 of the frame 2 is designed to rest when said frame is disposed in operative position for supporting a mail bag. (See Figs. 1 and 2.) The upper edge of this plate 7 is inclined downwardly from opposite sides of said recess 9 as shown at 10 and said inclined edge terminates at its outer or rear ends in sockets 11 disposed at opposite sides of the 70 bracket 7 and which are designed to receive the arm 3 of the frame 2 when the crane is 75 in inoperative position. (See dotted lines in Fig. 2.)

Projecting upwardly from the side edges 80 of the bracket or plate 7 are arms 12 which terminate in a plane above the recessed portion 9 of said plate and are adapted to form guides for the arm 3 of the frame 2 to prevent it from riding out of the sockets 11 85 when swung roughly to one side or the other as would occur when the mail bag is gripped by the catching device of a fast moving train, it being obvious that this gripping movement of the mail bag will 90 cause the frame 2 to swing laterally out of the recess 9 to one side or the other according to the direction in which the train is moving and when so swung will ride 95 downwardly on the inclined edges 10 and drop into one of the sockets 11 at the side of the bracket toward which it has been 100 swung by the moving train.

From the above description it will be 105 obvious that this crane or supporting frame 110 2 will be swung automatically into inoperative position by the removal or disen-

gagement of the mail bag therefrom, thus obviating the necessity of an operator being required for this purpose. It will of course be understood that when the bag is 5 to be supported in position ready to be delivered to a passing train that it will be necessary for the operator to swing the frame 2 around into position to cause the arm 3 thereof to engage the recess 9 in the upper edge of the bracket 7 and when so 10 swung the loops L of the bag B will be engaged with the arms 3 and 4 as shown in Fig. 1 and thus held suspended ready to be delivered.

15 This device while very simple in construction constituting three parts only, is very efficacious in operation and will deliver a mail bag as reliably as more complicated structures and there are no parts 20 which can get out of order.

The rod constituting the body portion of the frame 2 is of a length greater than the distance between the clip 5 and the bracket 7 which form bearings therefor to adapt 25 said rod to be moved longitudinally in said bearings to provide for the downward movement of the arm 3 into one of the sockets 11 of the bracket 7 when said arm is swung into inoperative position, said 30 sockets being disposed in a plane below the recess 9 which supports said arm in operative position. Hence it will be observed that this frame 2 is adapted to move longitudinally and to swing transversely in the 35 bearings provided by the clip 5 and bracket 7.

I claim as my invention:

1. A mail bag crane comprising a supporting structure, vertically spaced bearings mounted thereon, a rod mounted to 40 slide longitudinally and to swing laterally in said bearings, arms extending laterally from opposite ends of said rod, one of said 45 bearings being substantially U-shaped in cross section and provided on its upper edge with a recess disposed midway its ends and recesses spaced laterally from said first mentioned recess to receive and support the

upper arm of said rod and the weight of the bag carried thereby to hold said rod against 50 downward dropping.

2. A mail bag crane comprising a supporting structure, vertically spaced bearings mounted thereon, one of said bearings comprising a bracket U-shaped in cross section 55 secured at its opposite ends to said supporting structure and having a recess disposed midway its ends in its upper edge, said upper edge inclining downwardly from said recess and terminating at its rear ends 60 in sockets, a rod disposed in said bearings and of a length greater than the distance between the bearings to provide for its longitudinal movement therein, and arms extending laterally from opposite ends of said 65 rod, one of said arms extending above and adapted to be seated in said recess and sockets respectively to hold the rod in adjusted position.

3. A mail bag crane comprising a supporting structure, vertically spaced bearings mounted thereon, one of said bearings comprising a bracket U-shaped in cross section 70 secured at its opposite edges to said supporting structure and having a recess 75 disposed midway its ends in its upper edge, said upper edge inclining downwardly from said recess and terminating at its rear ends in sockets, a rod disposed in said bearings and of a length greater than the distance 80 between the bearings to provide for its longitudinal movement therein, and arms extending laterally from the opposite ends of said rod, said bracket being provided at 85 its upper end at the sides thereof with longitudinally extending arms projecting in a plane above the recessed portion of said bracket.

In testimony whereof I have hereunto set my hand in presence of two subscribing 90 witnesses.

RUFUS E. MOODY.
